WASHING MACHINE

William Baxter Glisson, Trenton, Tenn.

Application October 6, 1942, Serial No. 460,990

3 Claims. (Cl. 68—122)

The present invention relates to new and useful improvements in washing machines of the manually operable type, and has for one of its important objects to provide, in a manner as herein-after set forth, a device of this character which is adapted to be conveniently used in conjunction with a conventional wash tub.

Another very important object of the invention is to provide a washing machine of the aforementioned character comprising a pounder of novel construction for thoroughly cleaning the clothes.

Other objects of the invention are to provide a washing machine of the character described which will be comparatively simple in construction, strong, durable, highly efficient and reliable in use, compact, light in weight, and which may be manufactured at low cost.

All of the foregoing and still further objects and advantages of the invention will become apparent from a study of the following specification, taken in connection with accompanying drawings wherein like characters of reference designate corresponding parts throughout the several views, and wherein:

Figure 1 is a view in side elevation of a washing machine constructed in accordance with the present invention, showing the supports and the tub in section.

Figure 2 is a top plan view.

Figure 3 is a view in front elevation, showing the tub in section substantially on the line 3—3 of Figure 2.

Figure 4 is a view in vertical section through the pounder, taken substantially on the line 4—4 of Figure 1.

Figure 5 is a cross-sectional view, taken substantially on the line 5—5 of Figure 2.

Figure 6 is a cross-sectional view, taken substantially on the line 6—6 of Figure 1.

Figure 7 is a view in vertical longitudinal section through the connection between the lower end of the lever brace and the stand.

Referring now to the drawings in detail, it will be seen that the embodiment of the invention which has been illustrated comprises a folding tub stand 1 of suitable metal. The stand 1 includes a horizontal tubular frame 2 which is mounted on a pair of substantially U-shaped supports 3. The supports 3 converge upwardly, the legs 4 thereof being pivotally secured at 5 to the tubular side bars of the frame 2. The legs 4, on one side of the stand 1, include extensions 28 which are detachably connected by a bolt 6 for 55

securing the supports 3 in open or operative position. The extensions 28 are provided, at intermediate points, with openings 29 which, when in registry, receive the bolt 6 for securing the supports 3 in folded or inoperative position.

Mounted on the side portions of the frame 2 is a pair of upwardly converging standards 7. A hand lever 8 is journaled for swinging movement in a vertical plane on a pin 9 between the upper end portions of the standards 7. A brace 10 is provided for the standards 7. Mounted on the rear end portion of the frame 2 is a cross member 11. A bracket 12 is mounted on the cross member 11. One end portion of the brace 10 is detachably secured to the cross member 11 through the medium of a removable pin 13, which is inserted through openings provided therefor in said brace, the bracket 12 and said cross member. The other end portion of the brace 10 has 20 mounted thereon angular bars 14 through which the pin 9 passes, said bars projecting between the upper end portions of the standards 7 and the lever 8.

Mounted on the forward end of the lever 8 is a pounder 19. The pounder 19 includes a vertical rod 15 which is adjustably and removably mounted on the lever 8. Toward this end, the rod 15 has formed therein a series of spaced openings 16. Mounted on one side of the lever 8 and projecting 25 forwardly therefrom is a hook 17 (see Fig. 2) which is engageable selectively in the openings 16. An arm 18 is pivotally mounted on the other side of the lever 8 and projects forwardly therefrom for retaining the rod 15 on the hook 17. A pin 30 supports the pivoted retaining arm 18 in 30 operative position on the lever 8.

The pounder 19 further includes, in the embodiment shown, a pair of superposed, flanged, inverted frustoconical cups 20 and 21. The rod 15 passes through the top of the inverted cup 21 and is firmly secured to the corresponding portion of the lower cup 20. Mounted concentrically in the lower cup 20 is a plurality of comparatively small cups 22. Braces 23 extend from the rod 15 through the top of the cup 21 and are secured to the top of the cup 20. The lower end portions of the braces 23 project outwardly beyond the periphery of the cup 20 and are bent upon themselves in a manner to provide guard fingers 24 the purpose of which will be presently set forth. Bars 25 are mounted on the cup 20 on opposite sides of the rod 15.

It is thought that the operation of the device will be readily apparent from a consideration of the foregoing. Briefly, a conventional wash

tub 26, for the reception of the clothes, is supported in elevated position on the forward portion of the frame 2 and the pounder 19 is engaged therein. Thus, a fire may be conveniently built beneath the tub. Of course, the tube 26 is filled to the desired level with water. Through the medium of the hand lever 8, the pounder 19 is then moved upwardly and downwardly in the tub 26 for sucking the clothes upwardly and then forcing them downwardly. The construction and arrangement is such as to force water and air through the clothes in a manner to thoroughly and rapidly clean them. The guards 24 prevent the clothes from working past the pounder 19 in the tub 26. The substantially frusto-conical cup 21, together with the braces 23 and the bars 25, prevent the clothes from coming to rest on top of the pounder 19. The standards 7 are pivotally connected to the side bars of the frame 2 at 27. Thus, by withdrawing the pin 13 and disconnecting the supports 3 at 6, the device may be folded in a manner to occupy a minimum of space when not in use. The supports 3 are swung upwardly on their pivots 5 to align the openings 29 in the extensions 28. The bolt 6 is then transferred to the openings 29 for securing the supports 3 in folded or inoperative position on the frame 1. The device may then be hung on a pair of nails on a wall, for example, by engaging the nails in the openings in the free end portions of the extensions 28 from which the bolt 6 was removed. The plunger 19 may be removed and hung on another nail engaged in one of the openings 16 in the rod or stem 15 of said plunger.

It is believed that the many advantages of a washing machine constructed in accordance with the present invention will be readily understood, and although a preferred embodiment of the device is as illustrated and described, it is to be understood that changes in the details of construction and in the combination and arrangement of parts may be resorted to which will fall within the scope of the invention as claimed.

What is claimed is:

1. A washing machine of the character described comprising a stand for supporting a tub, a cross member on said stand, a pair of upwardly converging standards pivotally mounted on the stand, an angular bracket on the cross member, a brace for the standards having one end portion engaged between the bracket and the cross member, a removable pin engaged in the bracket, said one end portion of the brace and the cross member for detachably securing said brace to the stand, a lever pivotally mounted on the standards, and a pounder mounted on one end portion of said lever.
2. A washing machine of the character described comprising a supporting structure, a lever pivotally mounted on said supporting structure and a pounder mounted on the lever, said pounder including a rod on one end of the lever, substantially frusto-conical, inverted upper and lower cups on said rod, a plurality of comparatively small cups mounted concentrically in the lower cup, and braces extending from the rod through the upper cup and secured to the lower cup, said braces terminating in outwardly projecting lower end portions constituting guards projecting beyond the periphery of the lower cup.
3. A washing machine of the character described comprising a supporting structure, a lever pivotally mounted on said supporting structure, and a pounder mounted on the lever, said pounder including a vertical rod having a series of openings therein, a hook projecting from one end portion of the lever and engageable selectively in the openings for adjustably mounting the rod on said lever, an arm projecting from said one end portion of the lever and engaged with the rod for retaining said rod on the hook, and a cup mounted on the rod.

WILLIAM BAXTER GLISSON.
